US0D1000469S

(12) **United States Design Patent** (10) Patent No.: **US D1,000,469 S**
(45) Date of Patent: ** Oct. 3, 2023

(54) **DISPLAY SCREEN OR PORTION THEREOF
WITH GRAPHICAL USER INTERFACE**

(71) Applicants: **YOKOGAWA ELECTRIC
CORPORATION**, Musashino (JP);
**YOKOGAWA TEST &
MEASUREMENT CORPORATION**,
Musashino (JP)

(72) Inventors: **Ayako Kouno**, Tokyo (JP); **Daisuke
Sato**, Tokyo (JP); **Yang Feng**, Tokyo
(JP); **Gentarou Ishihara**, Tokyo (JP)

(73) Assignees: **YOKOGAWA ELECTRIC
CORPORATION**, Tokyo (JP);
**YOKOGAWA TEST &
MEASUREMENT CORPORATION**,
Tokyo (JP)

(**) Term: **15 Years**

(21) Appl. No.: **29/850,324**

(22) Filed: **Aug. 18, 2022**

Related U.S. Application Data

(62) Division of application No. 35/512,016, filed on Dec.
10, 2020 (U.S. filing date under 35 U.S.C. 384), and
having an international filing date of Dec. 10, 2020.

CLAIM

The ornamental design for a display screen or portion
thereof with graphical user interface, as shown and
described.

DESCRIPTION

The sole FIGURE is a front view of a display screen or
portion thereof with graphical user interface showing our
new design.

The peripheral dashed broken lines illustrate a display
screen or portion thereof, and form no part of the claimed
design.
